UNITED STATES PATENT OFFICE.

CHARLES E. BENEDICT AND PHILIP NORDECK, OF CINCINNATI, OHIO.

CIGAR-MOLD.

1,109,817.

Specification of Letters Patent.

Patented Sept. 8, 1914.

Application filed August 9, 1913. Serial No. 783,906.

To all whom it may concern:

Be it known that we, CHARLES E. BENEDICT and PHILIP NORDECK, citizens of the United States, and residents of the city of Cincinnati, in the county of Hamilton and State of Ohio, have invented certain new and useful Improvements in Cigar-Molds, of which the following is a full, clear, and exact description, reference being had to the accompanying drawings, forming a part of this specification.

In the manufacture of cigar molds the greatest difficulty is to obtain a mold which will not warp or bend and in which the cups and matrices will not slip out of place or become bent and broken.

It is the object of this invention to provide a cigar mold which is safeguarded against these difficulties and this we accomplish by that certain construction and arrangement of parts to be hereinafter specifically pointed out and claimed.

In the drawings,—Figure 1 is a perspective view of the cigar mold in closed position. Fig. 2 is a central vertical section thereof, taken through a cup. Fig. 3 is a side elevation of the same taken from the opposite side to that of the perspective in Fig. 1, and Fig. 4 a perspective of the lid of the mold, inverted, and partly broken away.

1 is the bottom of the mold and 2 the matrix, preferably cross-grain to the bottom or backing. The preferred woods in the art for bottom and matrix are poplar for the bottom and beech for the matrix portion.

3 is the lid of the mold and 4 the cups.

It is desired in the matter so far mentioned to employ the usual forms well known to the art. Posts 5 are placed on the lid portion as is usual in the art and proper holes for them provided in the bottom portion.

The special shape and form of matrix or mold shown in the drawings is merely the form adopted for illustration, it being understood that the features so shown vary with each mold, being regulated by the shape of cigar that it is desired to press between the cups and the matrices of the two parts of the mold. The novelty resides in the method of reinforcing the construction as will be fully developed.

Although it is not a necessary feature of our device, it may be noted that the mold is made up in the usual way before the reinforcement is applied. That is, the matrix

piece is glued on to the bottom, and the cups are glued on to the lid. The posts are also placed in the lid, thus making a complete mold after the old pattern. Each one of these parts of a mold is reinforced after the mold is made up.

To reinforce the bottom and the matrices, there is set into the wood the strips 6—6. They are set in horizontally in each side of the completed bottom between the bottom piece and the matrices, and so positioned that the inside edges of the strips bear on both the poplar and the cross-grain of the two pieces, as indicated at 6' (Figs. 1 and 2). The fact that the reinforcing strip is set up against both of the pieces, makes much more for the strength of the union of the two, than if, say, it extended clear across between them and did not abut on either piece at any point, or if it was set into one of the pieces only. To slide at all, or to warp out of line, with the structure described would only occur when a number of glued surfaces had come apart, instead of upon the separating of but one glued surface.

To reinforce the lid and cups, there is set into the wood the strips 7—7—7. No special number of strips is desired to be specified. They are to be set into the wood vertically, and it is preferred to have them run the whole length of the lid from end to end, and to extend entirely through the lid portion proper, and part way into the base portion of the cups. It is desired to have one of the strips set into the posts 5. This strip would then extend through the post as far as it was set into the lid portion, and partly beyond the inner surface of the lid. The fact that the strips extend into the base portion of the cups as indicated at 8—8, as is plain, holds the cups from lateral movement on the lid. This is a very important matter in the art of mold construction because the cups are often of quite delicate construction, and a slight shifting or raising would cause them to break, as well as to spoil the article being molded. To warping, these strips also present an effective bar, because the shrinking or expanding preliminary to warping is stopped by the strips, owing to the fact that they are set into the bases of the cups.

The feature in connection with the reinforcement of the post has the obvious advantage of keeping it in place, and the post

also acts, in turn, on the strip, to make firmer its attachment. The curling or warping of the lid itself is effectually stopped. The lid is divided into as many parts plus 5 one as there are strips inserted, glued to the bases of the cups, and glued to the strips; and this structure is very effective in preventing the warping and curling so common in the art.

10. The number of strips in the lid and cups would be, of course, determined by the size of mold desired and by the expense of manufacture, but we prefer to use at least three, because the placing of wet tobacco within 15 the mold, and the damp atmosphere in which goods in the process of molding must be kept, make the probability of warping very great.

We preferably set the reinforcing strips 20 into the parts of the mold by sawing a proper kerf for them in the completed molds as above mentioned, and gluing them in place. We do not, however, wish to be limited to any one way of making up the reinforced molds.

Having thus described our invention, what we claim as new and desire to secure by Letters Patent, is:—

1. In a device of the character specified, 30 a means of reinforcing and holding against displacement the parts of the same, comprising strips of wood set in between the surfaces to be reinforced and engaging the surfaces in more than one plane.

2. In a cigar mold of the character specified, 35 a means of reinforcing and holding against displacement the parts of the same, comprising strips of wood set in between

the surfaces to be reinforced and engaging the surfaces in a lateral and a vertical plane. 40

3. In a cigar mold of the character specified, a means of reinforcing and holding against displacement the parts of the same, comprising strips of wood, set in between the surfaces to be reinforced, each strip engaging each surface between which it is situated in a lateral and a vertical plane. 45

4. In a cigar mold of the character specified, a means of reinforcing and holding against displacement the parts of the lid 50 thereof, comprising a plurality of strips set vertically in the lid piece and extending into and engaging the cup pieces, for the purpose described.

5. In a cigar mold of the character specified, 55 a means of reinforcing and holding against displacement the parts of the lid thereof, comprising a plurality of strips set vertically in the lid piece, one of said strips being set into the connecting posts of said mold, and said strips extending into and engaging the cup pieces, for the purpose described.

6. In a cigar mold of the character specified, 60 a means of reinforcing and holding against displacement the bottom and matrices thereof, comprising a plurality of strips set horizontally in the bottom, said strips extending into and engaging the matrices, for the purpose described.

CHARLES E. BENEDICT.
PHILIP NORDECK.
